UNITED STATES PATENT OFFICE.

IRVIN J. MAHA, OF WICHITA FALLS, TEXAS.

MOTOR-STARTER.

1,290,620.

Specification of Letters Patent. Patented Jan. 7, 1919.

Application filed November 9, 1917. Serial No. 201,093.

To all whom it may concern:

Be it known that I, IRVIN J. MAHA, a citizen of the United States, residing at Wichita Falls, in the county of Wichita and State of Texas, have invented new and useful Improvements in Motor-Starters, of which the following is a specification.

This invention relates to automatic starters for motors, and its primary object is to provide a spring starter which is simple of construction, reliable and efficient in action, and adapted to be rewound or reenergized by the power of the motor itself.

A further object of the invention is to provide clutch devices of a reliable and efficient type for connecting one portion of the starter spring with the motor shaft for rewinding action when necessary and for connecting another portion of the motor spring with the motor shaft for utilizing the power of said spring to start the motor.

The invention consists of the features of construction, combination and arrangement of parts, hereinafter fully described and claimed, reference being had to the accompanying drawing, in which:

Figure 1 is a vertical longitudinal section through the starter and crank case of the motor, showing the starter in normal or vertical position.

Fig. 2 is a vertical transverse section on line 2—2 of Fig. 1.

Fig. 3 is a vertical transverse section on line 3—3 of Fig. 1.

Fig. 4 is a detail section on line 4—4 of Fig. 1.

Referring to the drawing, 1 designates the crank case of a motor, 2 the engine crank shaft, 3 the projecting end of the shaft upon which the starter is mounted, and 4 a portion of the frame of the engine of the machine or vehicle driven thereby. In the present instance I have shown the starting mechanism arranged to transmit motion to the engine shaft in a counter-clockwise direction, but it is to be understood that, dependent upon circumstances or conditions, the starting mechanism may be arranged to transmit starting motion to the motor shaft in either a clockwise or a counter-clockwise direction.

The starter comprises a spring starting motor, of the coiled or spiral spring type, the coiled motor spring 5 being arranged within an inclosing drum or casing comprising a pair of spaced disks 6 and 7, and an annular

wall 8 carried by one of the disks, in the present instance the disk 7. The wall 8 projects from the peripheral edge of the disk 7 toward the peripheral edge of the disk 6 and carries an annular series of rollers 9 engaged by the peripheral edge of the disk 6, whereby a proper bearing for the outer edge of the disk 6 is afforded and provision made to adapt said disks to have independent rotary motion while coming close together and forming an inclosing casing for the spring 5, to shield and protect said spring from liability of injury.

The disk 6 is provided with a hub or sleeve 10 projecting within the spring casing and toward the disk 7. To this hub or sleeve 10, which is loosely mounted on the shaft section 3, is secured the inner end of the spring 5, the outer end of which is suitably fastened to the inner periphery of the wall 8, and hence through said wall to the disk 7. The disk 7 is loosely mounted for rotation on the shaft section 3, and said disks 6 and 7 are held in properly spaced relation by the sleeve 10, which holds them from sliding motion toward each other, and by collars 11 and 12, which respectively hold said disks from outward relative sliding motion on said shaft section 3.

The disk 6 is employed for transmitting motion from the motor shaft to the spring for rewinding or retensioning said spring, while the disk 7 is employed as a driving element for transmitting motion from the spring to the shaft for starting the motor into action. Formed upon the outer side of the disk 6 is a friction clutch member 13, having a beveled or tapered internal friction face, adapted to be engaged by the corresponding beveled friction face of an adjustable clutch member or disk 14, whereby the disk 6 may be connected with the shaft for transmitting motion thereto to rewind the spring and thereafter disconnect it therefrom to allow said disk to be held stationary while the shaft revolves. The clutch member 14 is provided with a sleeve 15 feathered to slide upon and rotate with the shaft section 3, as shown at 16, and said sleeve is angularly grooved to receive projections upon the forked end 17 of a bell-crank lever 18. This lever 18 is connected by a rod 19 with any suitable type of operating device for throwing the clutch member 14 into and out of action, a spring 20 also being provided to assist in throwing the

110

lever 19 out of action and to normally maintain it in retracted position. Formed upon the periphery of the clutch member 13 is an annular series of ratchet teeth 21 for engagement with a pivoted dog or pawl 22. The dog or pawl 22 is pivoted to the frame piece 4 and provided with arms 23 on which act springs 24 for normally holding the pawl in engaging position, while permitting it to ride over the inclined surfaces of the ratchet teeth. The pawl allows the disk 6 to be rotated by the friction clutch members 13 and 14 in one direction to wind up the motor spring 5, and automatically locks the disk 6 from rotation in the opposite direction for an obvious purpose.

The disk 7 is provided upon its outer face with a friction clutch member 25, similar to the clutch member 13, and which is adapted to be engaged by a clutch member 26, of similar construction to the clutch member 14. The clutch member 26 is provided with a sleeve 27 feathered to slide upon and rotate with the shaft section 3, as shown at 28, and having suitable connection with the forked end 29 of a bell-crank lever 30, whereby the disk 26 may be shifted into and out of engagement with the disk 25. Connected with the lever 30 is a rod 31 leading to a suitable type of operating device (not shown) whereby the clutch member 26 may be thrown into and out of engagement with the clutch member 25. A spring 32, similar to the spring 20, is provided for action upon the lever 30 to assist in retracting the clutch member 26 and to normally serve to hold it in retracted position. When the clutch member 26 is thrown into engagement with the clutch member 25, the disk 7 is fixed to the shaft section 3 for rotation therewith, so that when said disk 7 is free to revolve under the action of the spring 5 the power of the spring will be utilized for transmitting motion to the shaft section 3 to start the motor into action.

The disk 7 is normally held from motion in a motor starting direction by pawl and ratchet mechanism comprising an annular series of ratchet teeth 33, formed upon the periphery of the clutch member 25, which ratchet teeth are adapted for engagement with a pawl 34 pivotally mounted upon the frame piece 4, said pawl having arms 35 connected with springs 36 whereby the pawl is normally held in engagement with the shoulders of the ratchet teeth to lock the disk 7 against movement in one direction, while permitting the pawl to slide freely over the ratchet teeth to permit rotary motion of the disk 7 in the opposite direction. The pawl normally holds the disk 7 fixed against rotation by the action of the spring 5, so that the spring is normally maintained in a rewound or tensioned condition. By, however, throwing the pawl 34 out of en-

gagement with the ratchet tooth with which it is engaged, it will be obvious that rotary motion of the disk 7 through the power obtained from the uncoiling of the spring will be permitted, and that, in such action, when the clutch members 25 and 26 are in engagement motion will be transmitted to the shaft section 3 to start the motor. For the purpose of automatically retracting the pawl 34 when the clutch member 26 is thrown into action, the said pawl is provided with a beveled nose or projection 37 which lies in the path of the beveled face of the clutch member 26, said clutch member thus serving to swing the pawl 34 to a release position and hold it in such position, as long as said clutch member is in engagement with the clutch member 25, to permit the disk 7 to be revolved by the unwinding motion of the spring 5.

It will thus be understood that, assuming the spring 5 to be tensioned or wound for action, such spring will be normally held from unwinding by the locking action of the dogs 22 and 34, but that when the clutch 26 is thrown into action the dog 34, which normally holds the spring from rewinding motion, will permit the spring to unwind for revolving the motor shaft to start the motor, the spring being locked against further unwinding motion, after the starting of the motor, by the retraction of the clutch member 26, which allows the pawl 34 to again move back to starting position. The spring may be of such size and power as to be capable of starting the motor a number of times before it requires to be rewound. At any time when the engine is in motion it will be evident that the spring may be rewound by simply throwing the clutch member 14 into action. Any suitable means may be provided for indicating when the spring is fully wound, or this may be determined by the judgment of the operator or "feel" of the operating device connected with the rod 19, since, as soon as the spring approaches a fully wound condition and its resistance increases there will be a tendency of the clutch member 14 to slip, the motion of which may be detected by the hand of the operator holding the control device. Any suitable or well known means may, however, be employed for automatically throwing the clutch member 14 out of action when the spring is fully rewound.

My invention provides a simple, reliable and efficient form of spring starter for the motors of traction engines, automobiles and like machines or vehicles driven by internal combustion engines, which starter is of a character which may be primed for operation at intervals by the power of the running motor and may be thrown into action to start the motor in a positive and reliable manner. The starter may be provided at

any suitable point along the length of the motor shaft, according to the arrangement of the motor upon the machine or vehicle.

In practice a suitable tool or clutch lever 5 may be employed for engagement with the ratchet teeth 21 of clutch member 13 for the purpose of initially winding up the spring 5 or at other times manually winding it up when desired or required. Also a pawl and 10 ratchet mechanism of ordinary type may be employed in connection with the sleeve 27 of clutch member 26, to hold said clutch member from retrograde rotation, to obviate liability of damage to the starter 15 mechanism in the event of the engine back-firing.

Having thus fully described my invention, I claim:

1. In a motor starter, the combination of 20 an engine shaft, a pair of spaced disks loosely mounted on said shaft, a coiled power spring fixed at its ends to the respective disks, pawl and ratchet devices for holding each disk against motion in one direction 25 while permitting it to have motion in the opposite direction, a clutch device for connecting one of said disks with the shaft for communicating motion from the shaft to wind up the spring, and a clutch device for 30 connecting the other disk with the shaft, the holding pawl associated with said disk having a cam which lies in the path of shifting movement of said clutch device, whereby the said holding pawl may be retracted and 35 the disk simultaneously coupled to the shaft for transmitting power from the spring to the shaft for a motor starting action.
2. In a motor starter, the combination of an engine shaft, a pair of spaced disks

loosely mounted on said shaft, one of said disks having a hub and the other an annular wall, and said disks collectively forming an inclosing casing, a spiral power spring 40 inclosed within said casing and fixed respectively at its opposite ends to said sleeve and wall, friction clutch members carried by the respective disks, said clutch members being provided with ratchet teeth, clutch members feathered to the shaft and movable into and out of engagement with the first named 45 clutch members, means for operating the second named clutch members, and dogs for engaging the ratchet teeth to hold the disks from motion, one of said dogs being adapted 50 to be automatically retracted by engagement with the coacting sliding clutch member.

3. In a motor starter, the combination of a motor shaft, a pair of spaced disks loosely mounted on said shaft, one of said disks having a central hub and the other a laterally projecting peripheral wall, said parts cooperatively forming a casing, a coiled spring inclosed within said casing and 60 respectively connected at its ends with said sleeve and peripheral wall, friction clutch 65 members upon the outer faces of said disks, said clutch members being provided with ratchet teeth, locking dogs mounted upon a stationary part of the frame to engage the ratchet teeth of the disks, a sliding friction clutch member on the shaft for engagement with one of said clutch members, and a sliding friction clutch upon the shaft for engaging the other clutch member and simultaneously contacting the coacting pawl to throw 70 the same out of locking position.

In testimony whereof I affix my signature.

IRVIN J. MINDA.
